CLOSURE ASSEMBLY FOR TANKS AND
OTHER CONTAINERSDonald M. Hintz, Northbrook, Ill., assignor to
Culligan, Inc., a corporation of Delaware

Application April 7, 1950, Serial No. 154,698

3 Claims. (Cl. 220—40)

1

The present invention relates to a novel closure assembly for the access opening of a tank or other container or vessel, and especially to a novel leak-proof cap or closure for sealing the fluid contents of the container, either gaseous or liquid and under pressure or vacuum, against leakage.

Among the objects of the present invention is the provision of a novel closure unit or assembly adapted for use with a pressure or gravity tank or container of the type that must be tightly sealed to prevent leakage, but which closure is susceptible of being easily and readily opened or removed to gain access to the interior of the container.

Another object of the present invention is the provision of a novel cap or closure so constructed and arranged as to require no pressure or force to effect sealing, other than that limited or negligible amount necessary to overcome the friction of the O ring. In prior types of structures designed for anchoring or locking a cap or closure on a container or vessel of the type here contemplated for containing a fluid under pressure, the application of considerable pressure against a gasket disposed between the vessel and the cap in order to effect a seal is required. In the present assembly, the cap or closure with its novel sealing arrangement is self-sealing in operation.

A further object of the present invention is the provision of a novel closure assembly including a novel means and manner of securing a rotatable type closure against accidental or unintentional removal when under fluid pressure.

The present invention further comprehends the provision of a novel safety locking means and mechanism for a cap or closure whereby to insure against accidental or unintentional removal or displacement when fluid pressure is exerted against the under side of the cap or closure by the fluid in the container.

Further objects are to provide a construction of maximum simplicity, efficiency, economy and ease of assembly and operation, and such further objects, advantages and capabilities as will later more fully appear and are inherently possessed thereby.

The invention further resides in the construction, combination and arrangement of parts illustrated in the accompanying drawings, and while there is shown therein a preferred embodiment, it is to be understood that the same is susceptible of modification and change, and comprehends other details, arrangements of parts,

2

features and constructions without departing from the spirit of the invention.

In the drawing:

Figure 1 is a view in front elevation of a tank equipped with the novel closure assembly.

Fig. 2 is an enlarged view in vertical cross-section through the closure assembly taken in a plane represented by the line 2—2 of Fig. 1.

Fig. 3 is a view in side or end elevation of the novel cap or closure for the assembly.

Fig. 4 is a view in side elevation of the disassembled flanged sleeve or collar upon which the cap or closure is mounted.

Fig. 5 is a top plan view of the flanged sleeve or collar of Fig. 4.

Fig. 6 is a fragmentary enlarged view of the locking flange of Fig. 4.

Fig. 7 is a view in perspective of the novel cap or closure removed from the assembly.

Referring to the disclosure in the drawing and more particularly to the novel illustrative embodiment shown, the present novel closure assembly comprises a cap or closure 10 and a flanged sleeve 11 mounted in the access opening and

providing a passage 12 opening into a tank or container 13, the cap or closure sealing the passage or opening in the sleeve against the escape of fluid, either gaseous or liquid, from the container. The tank or container shown is of the type now employed in water softener installations, but this showing is but illustrative in that the invention is not limited thereto but may be used on any type of tank or vessel containing fluid under pressure or vacuum, and regardless

of the size of the contemplated installation.

The novel cap or closure 10 is provided with a depending annular part 14 having on its circumference adjacent its lower end an outwardly opening continuous channel 15 adapted to receive and retain a resilient O shaped or toroidal ring 16 of flexible rubber-like material, preferably natural or compounded synthetic rubber.

This O or toroidal ring projects beyond the confines of the channel and seats and forms a self-sealing contact with the inner surface of the internal annular reduction 17 of the flanged sleeve 11. This flanged sleeve is shown as externally threaded at 18 and detachably received in an internally threaded collar 19 that may be welded or brazed to the tank or vessel 13. However, the flanged sleeve may be connected directly to the container without the use of the separate collar 19, if desired.

The cap or closure is further provided with an annular depending skirt 21 spaced from the de-

pending part 14 to form an annular and downwardly opening recess or channel 22 to receive the upper flanged end 23 of the sleeve 11. A transverse upstanding rib or projection 24 is formed integral with or affixed to the exterior of the cap or closure and extends diametrically across the same with each of its ends projecting downwardly over the depending skirt 21 and in-turned to form a locking lug or ear 25. This rib not only provides a strengthening means or reinforcement for the cap but also provides a handle or grasping portion for facilitating turning of the cap in its assembly and removal.

The upper end 23 of the flanged sleeve 11 is recessed to form entering notches 26 and elongated slots 27 each adapted to receive a lug or ear 25, and a flange 28 provided with a detent or depending safety catch 29 for preventing accidental or unintentional turning and release of the lug or ear 25 when the latter is received in the end of the slot 27 beneath the flange 28 and pressure within the tank or vessel forces the cap or closure upwardly with each lug or ear 25 seating against the lower edge of its flange 28 and locked behind the detent or catch 29.

Thus when the cap or closure 10 is mounted upon the flanged sleeve 11 with the lugs or ears 25 disposed within the entering notches 26, turning this cap or closure in a clockwise direction causes these lugs or ears 25 to enter the slots 27 beneath the flanges 28. Fluid pressure within the container 13 elevates the cap or closure and causes these lugs or ears to seat against the base or undersurface of the flange 28 and any tendency for the cap or closure to move in a counter-clockwise direction would be prevented by its engagement with the detent or safety catch 29. It will thus be evident that to disconnect and remove the cap or closure without relieving the pressure in the vessel or system in which the vessel is employed would require the application of sufficient force to depress the cap or closure to such an extent as to allow for the lugs or ears 25 to clear the detent or safety catch 29 and to rotate the cap or closure in a counter-clockwise direction while thus depressed, a task impossible in many installations.

A highly important feature of the present invention is that no pressure or force, other than that required to overcome the slight friction of the O or toroidal ring 16 against the interior 17 of the annular reduction of the flanged sleeve 11, is required in sealing this closure. No pressure against a gasket disposed between the cap or closure and a fixed seat as in prior installations, is required to effect sealing. As the O ring does not engage the interior of the sleeve or collar 11 until it reaches the annular reduction 17, it will be apparent this closure may be quickly assembled or removed when the occasion requires.

As for the size of the access opening and of the cap or closure, these may be of any dimensions required or suitable for the purpose, and if used for closing and sealing large openings the cover may be suitably hinged and additional spaced lugs or ears may be provided for most effective engagement and sealing. This would eliminate the use of lug bolts commonly used for closures.

It will thus be seen that the novel closure assembly of the present invention has a wide application of uses and upon vessels varying through a wide range of sizes. For example, this type of closure may be employed as a closure for manholes

for steam boilers, or any other type of large vessel where a closure of this type may be employed.

Having thus disclosed the invention, I claim:

1. A closure assembly for sealing an opening in a tank containing a fluid under pressure, comprising an upstanding sleeve in the opening in the tank and provided with an internal cylindrical reduction spaced from the upper end of the sleeve, a cap for closing and sealing the opening through the sleeve including a cylindrical flange depending into the opening in the sleeve and a resilient sealing ring carried by said flange adjacent its lower end and having sealing contact with the interior of the sleeve when moved into contact with the cylindrical surface of the reduction, notched recesses provided at spaced points about the upper end of the sleeve, a circumferential skirt depending from the cap in spaced relation with the flange to provide a downwardly opening annular recess therebetween for the reception of the upper end of the sleeve, an upstanding rib rigidly affixed to and extending diametrically across the cap for rotating the cap into locking engagement with the sleeve and provided at its opposite ends with inwardly projecting ears adapted to be received in the notched recesses at the upper end of the sleeve, and a safety catch in each recess for locking and retaining the ears against accidental displacement when the pressure within the tank is exerted against the cap.

2. A closure assembly for closing and sealing an opening in a container providing access to the interior thereof, a sleeve encompassing the opening and having an upstanding flange and an internal annular reduction intermediate its ends, spaced outwardly and upwardly opening notches provided in the outer circumference of the flange of the sleeve, a cap for closing the opening and sealing the contents of the container, and provided with a depending circumferential flange and a depending annular flange of substantially greater depth than and spaced inwardly from the circumferential flange to provide an annular downwardly opening channel therebetween adapted to receive the upstanding flange on the sleeve, an outwardly opening recess in the depending annular flange of the cap adjacent the lower end thereof, a resilient O sealing ring mounted in said last mentioned recess and projecting outwardly therefrom for sealing contact with the cylindrical interior of the annular reduction of the flange on the sleeve, inwardly projecting ears on the cap adapted to be received in the notches of the sleeve, and a catch for maintaining the ears engaged in the notches.

3. A closure assembly for closing and sealing an access opening in a container against the escape of fluid under pressure, comprising a sleeve mounted in the access opening having a part projecting beyond the exterior of the container and having at its upper end upwardly and outwardly opening spaced recesses, a locking flange and a depending locking detent at the end of the flange, a cap providing a closure for the opening and having an annular depending skirt and a depending annular flange forming a circumferential wall spaced inwardly of the skirt and forming with the skirt an annular downwardly opening channel for receiving the upper end of the sleeve, an outwardly opening annular channel in the lower end of the flange, a resilient sealing ring disposed within the last mentioned channel and between the interior of the sleeve and the exterior of the circumferential wall of the depending annular flange, and an upstanding rib extending diametri-

cally across the upper surface of the cap with the ends of the rib having inturned spaced lugs carried by and rigidly affixed to the annular skirt of the cap and adapted to be received in the spaced recesses of the sleeve and when the cap is rotated in one direction each lug seats beneath a locking flange and behind a locking detent and is held thereagainst by pressure from within the container and exerted against the interior of the cap.
